UNITED STATES PATENT OFFICE.

EDWIN B. STIMPSON, JR., OF BROOKLYN, NEW YORK.

DESIGN FOR TRIMMING.

SPECIFICATION forming part of Design No. 18,771, dated November 27, 1888.

Application filed October 1, 1888. Serial No. 286,893. Term of patent 3½ years.

To all whom it may concern:

Be it known that I, EDWIN B. STIMPSON, Jr., of the city of Brooklyn, in the county of Kings and State of New York, have invented and produced a new and original Design for Trim-
mings, of which the following is a specification.

My design is especially intended for trim-
mings made of leather.

I will describe my design in detail, and then
to point out the novel features in the claim.

The accompanying drawing illustrates my
design.

My design consists, essentially, of a zigzag
row of circles. In the example of my inven-
tion shown the zigzag row of circles comprises
two straight rows, each made up of groups of
four circles, *a*, and spaces *a'* between the said
groups. The spaces *a'* of one row are arranged

opposite a group of circles, *a*, in the other row.
The design is therefore substantially a zigzag 20
row of circles. Outside the rows of circles I
have shown scallops *c*, of alternate angular and
curved outline, whereby points and semicir-
cles are formed.

What I claim as my design is—
25
The design for trimmings, consisting of two
rows of circles, each row being composed of
groups of circles and spaces between the groups,
the groups of circles of one row being opposite
the spaces of the other row, and scallops out- 30
side of said rows, substantially as shown.

EDWIN B. STIMPSON, JR.
